UNITED STATES PATENT OFFICE.

JOHN MCCHESENEY, OF LOUISVILLE, KENTUCKY.

WASHING-MACHINE.

Specification of Letters Patent No. 15,043, dated June 3, 1856.

To all whom it may concern:

Be it known that I, JOHN MCCHESENEY, of Louisville, in the county of Jefferson and State of Kentucky, have invented a new and 5 useful Improvement in Washing-Machines; and I do hereby declare that the following is a full, clear, and exact description of the same, reference being had to the annexed drawings, forming part of this specification, 10 in which—

Figure 1 is a vertical section through axis of shaft on $\alpha\alpha$, Fig. 4. Fig. 2 is a vertical section through axis of shaft on $\gamma\gamma$, Fig. 4. Fig. 3 is a side elevation with segment of 15 disk elevated. Fig. 4 is a top view of machine.

Similar characters of reference in the several figures denote the same part.

The character of washing machine to 20 which my invention applies is that in which the operating parts consist of a tub and disk rubber.

The object of the invention is the loosening of the clothes at each partial revolution 25 of the disk rubber, to prevent their packing; thus greatly facilitating the washing operation.

The invention consists in suspending the disk rubber by cords passing over pulleys to 30 a horizontal pulley governed by a ratchet and pawl, so that the disk rubber may be adjusted in vertical position according to the quantity of clothes in the tub, and the cords kept tight in all such positions; and 35 in connection with the above, the invention further consists in the insertion in the lower face of the rubber, of rotary radial, fluted frustums of cones, projecting beyond the fluted face of the rubber, the action of these 40 conic frustums in connection with the adjustable suspension of the disk, for effecting the object specified aforesaid, will readily be understood from the following description and reference to the drawing, in 45 which—

A is the body of the tub having a fluted bottom.

B is the disk rubber, consisting of a central portion a , and two hinged flaps, c , kept 50 down when in operation by braces b . This construction does not however constitute an essential portion of my machine, as a solid disk would serve all purposes. The under surface of the rubber is fluted, and has inserted in it, so as to project beyond the 55 flutes, a number of radial frustums of cones

m fluted and capable of rotation, the small bores of the frustums being toward the center of the disk. This disk rubber is designed to be made quite heavy, weighing 60 about seventy-five pounds. This rubber is suspended by cords d d , passing over pulleys e e , to pulley f , which is held by cross piece C. This pulley f turns freely upon shaft D (which is stepped at g), and is held 65 in any desired position by ratchet i and pawl l ; lever k serves to turn this pulley. This construction serves to adjust the rubber vertically, independently of the operating mechanism. 70

The shaft D which passes through the rubber, has a cross section as shown at α ; so that as the said shaft is turned by lever G, the rubber will be moved with it. As the disk rubber is moved horizontally by 75 the shaft, it will be seen that the cords suspending the rubber will cause the said rubber to move longitudinally along the shaft D, so that the rubber will have a compound vertical and horizontal movement. 80

The operation of this construction upon the clothes is as follows. At each rise of the rubber the water is enabled to some extent to loosen the mass of clothes, which had been compressed by the previous action of 85 the rubber. As the rubber descends on this saturated mass, the fluted frustums projecting beyond the face of the disk, encounter the clothes before any other portion of the rubber, and by reason of their flutes loosen 90 the surface, for the action of the disk.

It will thus be seen that at each turn of the operating lever, the suspension of the disk and the fluted frustums act in conjunction to serve an important purpose in the 95 washing operation. That is—the suspending apparatus, by lifting the rubber, permits the flow of water to the compressed surface of the clothing, placing them in a condition to be easily loosened. This loosening is accomplished by the frustums, as the rubber descends on the clothes; by the catching of the flutes in the saturated and partially loosened surface. 100

That this loosening of the clothes is a 105 feature of great importance in this character of machines, will not need demonstration here. It may be mentioned that lever k serves to lift the rubber for removing the clothes.

I am aware that in the patent granted Joel Haines for a washing machine Feb. 110

5th 1850, the disk is made with a hinged segment, (to admit the clothes beneath the same), being so arranged as to rise and fall vertically as it is turned horizontally over 5 the clothes, by turning the vertical rock-shaft to the right and left. This feature I do not claim, my invention consisting only in an improvement upon the machine of said Joel Haines, to wit:

10 I claim—

The adjustable suspension of the rubber disk by cords, ratchet and pawl as described,

in combination with the rotary, radial fluted, frustums of cones in the rubbing face of said disk, operating substantially as, and 15 for the purposes set forth.

In testimony whereof, I have hereunto signed my name before two subscribing witnesses.

JOHN McCHESNEY.

Witnesses:

GEO. PATTEN,
JOHN S. HOLLINGSHEAD.
